LUBRICATOR FOR JOURNAL BEARINGS

Michael J. Nardulli, Elmwood Park, and Carl J. Delegard, Chicago, Ill.

Application July 13, 1951, Serial No. 236,522

4 Claims. (Cl. 308—83)

1

This invention relates to lubricators for railway journal boxes.

In a railway journal box such as the standard AAR journal box, a journal bearing resting on a journal is conventionally lubricated by oil-soaked waste that is contained in the lower portion of the journal box and which bears against and acts as a wick to apply lubricant to the lower surface of the journal. It has long been recognized that the tendency of the waste to travel upwardly into the space between the bearing and the journal has been a major cause of bearing failures, hot boxes and the like. In view of this long recognized source of journal box failures, many different expedients have been employed for holding the packing against undesired upward displacement. Such expedients have usually taken the form of packing retainers and have been subject to objection in many instances for the reason that they constitute extra equipment which complicates servicing the journal box. In view of this it is an important object of the present invention to improve and simplify the lubrication and servicing of journal boxes and to eliminate conventional waste and like materials in journal boxes. A further and related object of the invention is to afford an improved lubricating means for journal boxes that may be readily and easily removed and replaced and which by its very form and character is effectively retained in proper position in the journal box.

Other and further objects of the present invention will be apparent from the following description and claims and are illustrated in the accompanying drawings which, by way of illustration, show a preferred embodiment of the present invention and the principle thereof and what we now consider to be the best mode in which we have contemplated applying that principle. Other embodiments of the invention embodying the same or equivalent principle may be used and structural changes may be made as desired by those skilled in the art without departing from the present invention and the purview of the amended claims.

In the drawings:

Fig. 1 is a longitudinal sectional view showing a journal box equipped with a lubricator embodying the features of the invention;

Fig. 2 is a cross sectional view taken along the line 2—2 of Fig. 1 and showing the lubricator when it is completely filled with lubricant;

Fig. 3 is a view similar to Fig. 1 with the lubricant supply somewhat depleted;

Fig. 4 is a perspective of the lubricator;

2

Fig. 5 is a fragmental sectional view showing the supply fitting.

For purposes of disclosure the present invention is disclosed as embodied in a lubricator 10 adapted for individual insertion or removal with respect to railway journal box 11, as will hereinafter be explained. Thus, as shown in Fig. 1, the journal box 11, which is a standard AAR journal box of the most commonly used type, embodies a top wall 12, side walls 13, and a transversely arcuate bottom wall 14 which is sloped upwardly at its outer end edge as at 14F so that an outer end opening 15 is defined for the journal box. This opening is normally closed by a lid 15L that is pivoted at 17 at its upper edge on the outer end edge of the top wall 12. Within the journal box 11, a journal bearing 18 is disposed beneath and in engagement with a conventional wedge 19 that engages the top wall 12, and lateral lugs 20 on the journal bearing 18 have rearwardly facing surfaces that engage the forward faces of locating or side lugs 21 that are formed on the inside surfaces of the side walls 13. These side lugs 21 terminate in lower end lug portions 21L. The journal bearing 18 is of the usual or standard type and is arranged to bear on the upper arcuate portion of a cylindrical bearing surface 25B of a journal 25, and this journal 25 may have the customary outer flange 25F, which may, under certain circumstances, engage with the end of the journal bearing 18.

In the conventional use of the journal box arrangement shown in Fig. 1, the lower portion of the journal box is filled with oil-soaked material, such as waste, and such waste extends usually to the lower ends of the lug portions 25L and engages the lower portion of the bearing surface 25B so that this bearing surface is lubricated in the course of rotation of the journal 25, but under the present invention the conventional oil-bearing waste or the like is replaced by the lubricator 10.

It will be noted in Fig. 1 that the working or clearance space between the flange 25F and the forward edge of the bottom wall 14 of the journal box is relatively small particularly as to its dimensions as measured radially of the journal and axially or longitudinally of the journal, and the lubricator 10 of the present invention is so constructed and arranged that it may be readily and easily put into or removed from its operative position through this small clearance space. Thus, the lubricator 10 is made up of parts that are bendable and compressible so as to be adapted for insertion or removal through such small clearance space, and as shown herein the lubricator

3

comprises a bendable and collapsible lubricant container 30 adapted to underlie the bearing surface 25B of the journal 25 and having one or more lubricant feeding openings 31 in its upper surface. This container 30 has a bendable and compressible pressure applying base member 32 secured thereto so that when the complete unit is in place in a journal box, the pressure applying base member is compressed in a generally vertical sense and acts by virtue of its resiliency to press the container 30 upwardly toward the journal, thereby to apply resilient collapsing or flattening forces to the container 30 and by such forces the lubricant within the container 30 is gradually fed through the feed openings 31 onto the lower face of the journal 25.

The container 30 is formed from a resilient moldable material that is of such a nature as to be resistant to the action of grease or oil, and this material in the nature of a synthetic rubber such as that commercially known as neoprene. Thus as shown in Fig. 5, the container 30 is normally relatively flat and long, and has a top wall 30T and a bottom wall 30B that are formed with joining side and end walls 30S and 30E. The feed openings 31 are formed in the top wall 30T midway between its edges and are arranged in a longitudinally spaced relation so as to attain relatively wide distribution of the lubricant over the bearing surface 25B of the journal. The upper or outer face of the top wall 30T may be formed, as shown in Fig. 5, so that the outer ends of the openings 31 are countersunk as at 31C to afford lubricant pockets.

One end of the container 30 may be said to constitute the outer end of the container since it is located adjacent the open end of the journal box, and on this outer end means are afforded for filling the container 30 while the lubricator 10 is in position in a journal box. Such means in the present instance are afforded by a filling tube 34 having one end extended through the end wall 30E in sealed relation. At its other or outer end, the tube 34 has a conventional lubricating fitting 35 of the type used in automotive and machinery lubricating systems, and this fitting 35 includes the conventional check valve. With such an arrangement, the container 30 may be readily filled by injection of lubricant under pressure through the fitting 35, and such fitting is readily accessible when the lubricator is in place in a journal box as will be evident in Fig. 1 of the drawings.

The base member 32 may take different forms which are characterized in each instance by bendability and compressibility so that they may be inserted into or removed from the journal box and are capable of applying upward collapsing or lubricant feeding forces to the container 30. Thus in the embodiment shown in Figs. 1 to 5 of the drawings, the base member 32 is formed from the same material as the container 30 but with a foam-like consistency like foam rubber. This base member 32, as shown in Figs. 1 to 5, is permanently attached to the bottom wall 30B of the container 30, as by vulcanizing or by adhesive, and the width of the base member 32 is such that it bears against the sides of the journal box so as to hold the lubricator 10 in proper position within the box and beneath this journal.

The normal or expanded thickness of the base member 32 is at least great enough to substantially fully collapse the container 30 against the journal 25, but it will be recognized that such normal or expanded thickness may be somewhat greater than the dimension thus determined

where this is desired to assure the application of relatively great feeding forces to the container 30. In any event, however, the base member 32 must be compressible to such a thickness that the base member 32 and the container 30 may, as a unit, be inserted downwardly and inwardly into the journal box and through the narrow clearance space beneath the journal. When such insertion has been completed, the lubricator 10 assumes the general form shown in Fig. 3 with the resilience or expansion of the compressed base member 32 substantially collapsing the container 30 in an arcuate form against the journal 25.

The container 30 is then filled with lubricant by use of conventional automotive lubricating equipment which forces lubricant under pressure through the fitting 35. This, of course, serves to further compress the base member 32, as will be evident in Fig. 2.

Thus, while we have illustrated and described the preferred embodiment of our invention, it is to be understood that this is capable of variation and modification, and I therefore do not wish to be limited to the precise details set forth, but desire to avail myself of such changes and alterations as fall within the purview of the following claims.

We claim:

1. In a lubricator for mounting in a railway journal box beneath the journal to lubricate such journal, said lubricator comprising an elongated bendable and collapsible lubricant container adapted to underlie such a journal and having an upper wall with an upper surface adapted to embrace a substantial arcuate portion of such journal, said upper wall having a plurality of openings therein through which lubricant may be fed from such container onto the journal, filling means at one end of said container through which the container may be charged with lubricant while in place in a journal box, and a flexible and compressible base member located beneath and attached to said container to act between the container and the bottom wall of a journal box to apply collapsing and lubricant-feeding forces to said container.

2. In a lubricator for mounting in a railway journal box beneath the journal to lubricate such journal, said lubricator comprising an elongated bendable and collapsible lubricant container adapted to underlie such a journal and having an upper wall with an upper surface adapted to embrace a substantial arcuate portion of such journal, a flexible and compressible base member located beneath and attached to said container to act between the container and bottom wall of a journal box to apply collapsing and lubricant-feeding forces to said container, said upper wall having at least one opening therein through which lubricant may be fed from such container onto the journal, and check-valved filling means at one end of said container through which the container may be charged with lubricant under pressure while in place in a journal box to thereby fill said container and at the same time compress said base member.

3. In a lubricator for mounting in a railway journal box beneath the journal to lubricate such journal, said lubricator comprising an elongated bendable and collapsible lubricant container adapted to underlie such a journal and having an upper wall adapted to engage a bearing portion of such journal, said upper wall having at least one opening therein through which lubricant may be fed from such container onto the

journal, filling means for said container through which the container may be charged with lubricant, and means carried on the bottom of said container for applying yielding collapsing and lubricant feeding forces to said container.

4. In a lubricator for mounting in a railway journal box beneath the journal to lubricate such journal, said lubricator comprising an elongated bendable and collapsible lubricant container adapted to underlie such a journal and having an upper wall with an upper surface adapted to embrace a substantial arcuate portion of such journal, said upper wall having at least one opening therein through which lubricant may be fed from such container onto the journal, filling means at one end of said container through which the container may be charged with lubri-

cant while in place in a journal box, and means for applying collapsing and lubricant-feeding forces to said container comprising a flexible base member located beneath and attached to said container and expandable so as to act between the container and the bottom wall of a journal box to apply collapsing and lubricant-feeding forces to said container.
